United States Patent Office

Des. 202,187
Patented Sept. 7, 1965

202,187

BURIAL CASKET

John E. Alcott, Westwood, Mass., assignor to National Casket Company, Boston, Mass., a corporation of New York

Filed Feb. 3, 1965, Ser. No. 83,677

Term of patent 14 years

(Cl. D19—1)

Fig. 2

Fig. 1

FIG. 1 is a front elevational view of a burial casket showing my new design; and

FIG. 2 is an end elevational view thereof.

The rear and end not shown are identical to the front and end disclosed.

I claim:

The ornamental design for a burial casket, as shown and described.
